ASH RECEPTACLE

John Visser, Grand Rapids, Mich., assignor, by
mesne assignments, to Reconstruction Finance
Corporation, Detroit, Mich., a corporation of
United States

Application January 27, 1938, Serial No. 187,126

1 Claim. (Cl. 206—19.5)

This invention relates to ash receptacles and more particularly to ash receptacles of the type especially adapted for installation as an accessory in the instrument panel of an automobile or 5 the like.

An object of this invention is to provide an ash receptacle of such construction that it will occupy a minimum amount of space to the rear of the panel on which it is mounted.

10 Another object of this invention is to provide a compact ash receptacle of the foregoing type in which the ash container may be moved over an arcuate path into open and closed positions with a minimum amount of frictional resistance 15 to its movement.

Still another object of this invention is to provide an ash receptacle of the foregoing type in which the container and casing are so interrelated that the possibility of rattles between these 20 parts is reduced to a minimum.

In accordance with the general features of this invention, there is provided a tubular casing arcuate in a longitudinal direction and adapted to extend downwardly from the point of engagement of the outer end of the receptacle with the mounting panel, and an ash container of a similar configuration to that of the casing so as to telescope the same and have sliding engagement therein, and means for limiting outward movement of the ash container to its open position and which is manually deflectable to enable removal of the container from the casing when it is desired to empty the container.

Another feature of the invention relates to the 35 provision of a novel arcuate sliding arrangement between the container and its casing of such construction that the container may be moved to and fro in the receptacle with a minimum amount of frictional resistance being offered thereto and yet be held against rattling in the casing.

Other objects and features of this invention will more fully appear from the following detailed description taken in connection with the 45 accompanying drawing which illustrates a single embodiment thereof and in which:

Figure 1 is a front view of my novel ash receptacle showing it applied to a suitable panel;

Figure 2 is an enlarged sectional view taken 50 on the line II—II of Figure 1 looking in a direction indicated by the arrows and showing in dotted lines the position of the ash container when it is moved to an open position;

Figure 3 is a cross sectional view on a reduced 55 scale taken on line III—III of Figure 2 looking downwardly; and

Figure 4 is an enlarged fragmentary sectional view taken on the line IV—IV of Figure 1 looking 60 downwardly and showing the detail construction of the handle on the ash container.

The reference character 10 designates generally a longitudinally tubular and arcuate casing made from any suitable material, such for example as metallic sheets, and having its upper or outermost end suitably anchored or fastened 5 at 11 to the inner edge of the panel 12. The panel 12 has an opening of such configuration as to enable the tubular casing to snugly telescope and fit the same. In this instance it will be perceived that the casing has a rectangular cross 10 section (Figure 3) with its two lower corners bevelled as indicated at 13—13. Also, it should be noted that while the ash receptacle of my invention is especially adapted for use on an instrument panel such as that of an automobile 15 or other vehicle, it is, of course, capable of other applications wherever it is desired to use an ash container adapted to be concealed.

The outer or exposed end of the tubular casing 10 is provided with a beaded edge 14 which defines a recess or depressed seat 15 of rectangular configuration and in which finished outer panel 16 and ash container 17 are adapted to be seated. This construction is such that the assembly is provided with a substantially flush, smooth, and 20 pleasing appearance. Also, the outer surface of the panel 16 may be given any suitable finish, such, for example, as a grain finish to correspond with the finish on the panel 12 in which the ash receptacle assembly is installed. 30

In addition thereto the panel 16 has secured to it an outwardly projecting handle 18, which, as shown in Figure 4, is in the form of a segment of a circle so that its inner and flat side is contiguous and flush with the outer surface of the panel 16. This handle is suitably secured to the panel or end piece 16 by concealed means, namely bolt 19. Furthermore, the handle has its upper and lower sides recessed, as indicated at 20—20 in Figure 2, so as to provide a better finger grip. This handle may be made of any suitable material, such, for example, as a phenolic condensation product, and moreover it may be finished to blend with the appointments of the other knobs and handles employed on the instrument panel 12. 40

The ash container 17 is of tubular formation and is longitudinally arcuate as is evident from Figure 2. This configuration is such that it can nest inside of or telescope the casing 10. In 50 other words, it is of such longitudinal shape and cross sectional form that it may have a sliding movement inside of the casing which projects downwardly from its place of attachment to the instrument panel 12. 55

Then, too, it will be perceived from Figure 3 that when the ash container 17 is disposed within the casing 10, it is substantially spaced from the adjoining walls of the casing 10. It should also be noted from Figure 3 that the container 17 60

has a cross sectional configuration closely following that of the casing 10 but is generally of a substantially smaller size than that of the casing 10 so that it may telescope the latter.

5 The two lowermost corners of the container 17 are bevelled as indicated at 21-21, and these bevelled corners are directly inside of and opposite the bevelled corners 13-13 of the casing 10.

The two bevelled corners or sides 13-13 of the 10 casing 10 are each provided with a longitudinally extending arcuate rib or bead 22 for providing for substantially a line contact between each corner 13 and its adjoining and contiguous corner 21. It will, of course, be appreciated that these 15 longitudinally arcuate ribs or beads 22 could be disposed equally well on the corners or sides 21 as on the sides or corners 13. The purpose of this construction is to provide the ash container 17 with two sets of line contact slides which 20 facilitate the sliding movement of the container within the casing. That is to say, by having line contacts instead of surface contacts between the container 17 and the casing 10, it follows that there will be less frictional resistance to the sliding movement of the container within the casing.

In order to maintain the container in proper 30 cooperation with the slide ribs 22-22, a spring 25 is disposed at the top side of the container 17. This spring has its intermediate portion anchored by rivets or the like at 26 to a depressed section 27 formed in the upper or top wall of the container 17. The oppositely extending legs 28 and 29 have their free ends turned and disposed in tight, resilient engagement with the inner surface of two longitudinally extending ribs 30-30 formed in the top wall of the casing 10 (Figure 3). This arrangement is also advantageous in that it tends to minimize the amount of frictional contact between the container and the casing.

40 The forward or front end of the leg 29 of spring 25 is also provided with an extension 31 which has a cup-shaped depression 32, the bottom of which is suitably apertured as indicated at 33 (Figure 2). This extension serves two purposes 45 in my receptacle: one is to serve as a manually operable finger for releasing the spring from rocking engagement with the casing as will be described hereinafter; and the second is to provide a snapper on which the lit end of the cigarette or cigar may be applied to free the same 50 from ashes or to extinguish the same.

When the ash container 17 is moved forward 55 to its open position as shown by dotted lines in Figure 2, it will be perceived that the cup-shaped extension or finger 31 is then disposed outside of the casing 10, so that it is accessible for manipulation. At that time the uppermost extremity of the forwardly extending leg is in cooperation with an abutment 34 which comprises a downwardly 60 struck or depending portion formed integral with an interior part of the front end of the casing 10. This depending portion or abutment 34 is adapted to enter an aperture or slot 35 in the 65 uppermost portion of spring leg 29 so as to serve as a lock for holding the ash container in its open position and against further removal from the casing 10.

In addition to the foregoing, attention is directed to the fact that the upper side of the container 17 is cut away up to the edge 36 in Figure

2 so as to provide an opening through which ashes, cigars, cigarettes, matches, and the like can be disposed inside of the container 17. Likewise this opening also serves as a means for enabling the emptying of the container of its contents.

When it is desired to remove the container 17 from the casing 10 to empty the former, the same may be readily effected by manually depressing the cup-shaped extension 31 on finger 25 until 10 the upper end of the forwardly extending spring leg 29 clears the projection or abutment 34. Thereafter the container may be slid or drawn outwardly of the casing to a position where it is entirely free of the same. 15

Of course, during the normal sliding movement of the container 17 within the casing 10, it will be appreciated that the spring 25 constantly exerts a resilient pressure against the internal surface of the upper side of the casing 10, so that 20 the container is at all times urged downwardly into tight sliding cooperation with the spaced ribs 22-22 previously described. This feature prevents rattling of the container within the casing and yet enables the container to be slid to 25 and fro within the casing and with a minimum amount of resistance to such sliding movement.

I desire it understood that while I have illustrated the spring 25 as being carried by the container, this is only because this arrangement 30 is simpler and more economical to manufacture. The essential concept, however, relates to the disposition of the spring between the adjoining upper surfaces of the container and casing in such a manner that it can properly act to keep 35 the container in tight sliding engagement with the ribs 22-22.

I am aware that many changes may be made and numerous details of construction may be varied through a wide range without departing 40 from the principles of this invention, and I, therefore, do not purpose limiting the patent granted hereon otherwise than necessitated by the prior art.

I claim as my invention:

An ash receptacle especially adapted for use 45 on automobile instrument panels and the like comprising a casing of tubular construction and being segmentally circular in a longitudinal direction, an ash container of a configuration similar to that of the casing and telescoping the same for sliding movement therein to open and closed 50 positions, said casing having spaced longitudinally arcuate tracks and said ash container having longitudinal arcuate beveled surfaces engaging 55 said tracks for facilitating sliding movement of the container within said casing, and a manually depressable leaflike spring carried on the outer peripheral surface of the ash container between 60 said casing and ash container for engagement with an abutment on the casing to limit an opening movement of the ash container, said spring being manually depressable to disengage 65 it from said abutment when it is desired to entirely remove the container from or fully close it within the casing, said sliding movement occurring 70 under tension between said casing and container in a true radial direction in all telescopic positions.

JOHN VISSER. 70
